(57) **CLAIM**

The ornamental design for a buckle assembly, as shown.

DESCRIPTION

FIG. 1 is a front elevational view of a buckle assembly;
FIG. 2 is a rear elevational view of the buckle assembly;

FIG. 3 is a top plan view of the buckle assembly;
FIG. 4 is a bottom plan view of the buckle assembly;
FIG. 5 is a left side view of the buckle assembly;
FIG. 6 is a right side view of the buckle assembly;
FIG. 7 is a perspective view of the buckle assembly;
FIG. 8 is a front elevational view of a first part of the buckle assembly;
FIG. 9 is a rear elevational view of the first part of the buckle assembly;
FIG. 10 is a top plan view of the first part of the buckle assembly;
FIG. 11 is a bottom plan view of the first part of the buckle assembly;
FIG. 12 is a left side view of the first part of the buckle assembly;
FIG. 13 is a right side view of the first part of the buckle assembly;
FIG. 14 is a perspective view of the first part of the buckle assembly;
FIG. 15 is a front elevational view of a second part of the buckle assembly;
FIG. 16 is a rear elevational view of the second part of the buckle assembly;
FIG. 17 is a top plan view of the second part of the buckle assembly;
FIG. 18 is a bottom plan view of the second part of the buckle assembly;
FIG. 19 is a left side view of the second part of the buckle assembly;
FIG. 20 is a right side view of the second part of the buckle assembly; and,
FIG. 21 is a perspective view of the second part of the buckle assembly.
